Carl Anderson, Westfield, Mass.

Application July 1, 1937, Serial No. 151,482

3 Claims. (Cl. 76—31)

This invention relates to devices for use in filing saws and more particularly to a combination of saw clamping and file guiding devices for that purpose.

5 The principal object of the invention is to provide a device of this character which assures a greater degree of control of the filing characteristics without reliance on the individual skill of the operator than is afforded by prior devices, 10 and thereby to secure a better and more uniform result with a saving in time and labor.

Other and further objects residing in the details of construction will be apparent from the following specification and claims.

15 In the accompanying drawings which illustrate one embodiment of the invention,

Fig. 1 is a plan view of the structure;

Fig. 2 is an end elevation, parts being broken away;

20 Fig. 3 is a sectional view substantially on line 3—3 of Fig. 1;

Fig. 4 is a sectional view substantially on line 3—4 of Fig. 3, the carriage being omitted; and

25 Fig. 5 is a detail view showing the auxiliary supporting means for use with band saws.

Referring to the drawings, reference character 10 generally indicates a clamp or vise for holding the saw blade during the filing operation and which is preferably adapted to be secured to a 30 table or bench by any suitable means as indicated at 11 in Fig. 2. Clamp 10 comprises two jaw members 12 adapted to be clamped against the saw blade by a screw 13 provided with a wing nut 14. Preferably the lower ends of the

35 members 12 are provided with a quick release lever 15. The outer clamp member is provided with spaced lugs 16 pivotally receiving side 17 of the rectangular frame 18, the lugs 16 being provided with set screws 19 for holding the

40 frame in predetermined adjusted position in the lugs 16. The opposite side of frame 18 comprises rod 20 connected to end members 21 telescoping within end members 22 formed by bending the ends of side 17 at right angles, as best 45 shown in Fig. 1. End members 21 and 22 are held in adjusted telescoped relation by set screws 23. A file guide (generally indicated at 24) is pivotally and slidably mounted on rod 20. This file guide comprises two channel members 25 ar-

50 ranged back to back and held in spaced relation by end blocks 26, said parts being secured together by bolts 27. A supporting block 28 is rotatably and slidably mounted on rod 20, said block 28 being provided with a longitudinal opening 29 through which rod 20 passes. Block 28 is

pivoted at 30 to one of the channel members and the channel members are adapted to be clamped in predetermined angular relation with the block 28 by means of bolts 31. A file carriage 32 is reciprocably mounted in the upper channel member 25 (see Fig. 3). Said carriage comprises an inverted channel member 33 engaging beneath the inturned flanges of the channel 25 and provided at one end with means for receiving one end of the file 34. As shown this means comprises a chuck 35 in which the file non-rotatably engages, the chuck being slidably and rotatably mounted in a post 36 which is provided with a set screw 37 for holding the chuck in adjusted position. The other end of the carriage is provided with a suitable handle 38 by which the carriage may be reciprocated in the file guide 24. Intermediate its ends carriage 32 is provided with upright posts 39 in the upper ends of which a rod 40 is slidably mounted and held in adjusted 10 position by set screws 41. The forward end of rod 40 is provided with a block 42 in which the outer end of the file is secured by means of a set screw 43. Frame member 17 is provided on opposite sides of the clamp jaws 12 with posts 20 44 threaded for vertical adjustment in the frame member and held in adjusted position by nuts 45. The upper ends of posts 44 are apertured to receive a stop bar 46 held in place by means of set screws 47. Adjacent posts 44 are mounted in 25 inverted hooks 48 adapted to support a band saw as later described. Hooks 48 are held in vertically adjusted position in member 17 by means of set screws 49.

In operation a saw blade, indicated in dotted 35 lines at 50 in Fig. 2, is clamped in the vise 10. Frame 18 is adjusted for height and vertical angle by means of set screws 19 and the width of the frame is adjusted to accommodate the desired length of stroke of the file by means of set screws 23. The horizontal angular relation of the file guide 24 to the saw teeth is adjusted by loosening bolts 31, turning channel members 25 to the proper angular relation with the block 28, and tightening the bolts. The carriage 32 45 is then inserted in the uppermost channel 25.

As best shown in Fig. 2, the bar 46 is passed beneath rod 40 and by its engagement therewith limits the downward movement of the file. The desired degree of depth of cut of the file 50 is therefore secured by adjusting the height of the bar 46 by means of the threaded connection of the posts 44 in the frame and nuts 45.

When the edges of the teeth of the saw have been filed on one side, the carriage 32 is slid 55

from the guide 24 and the latter swung 180° around rod 20 when it assumes the position shown in dotted lines at A in Fig. 1. As is obvious the angle of the guide with respect to the saw is thus reversed and the carriage, when inserted in the now uppermost channel member 25, is in position for filing the other side of the saw teeth without readjustment.

In filing a band saw or the like the portion to be operated on is clamped on the jaws of vise 10, the adjacent portions being supported in vertical position by engagement beneath hooks 48 which are adjusted to accommodate the width of the particular saw by means of set screws 49.

15 I claim:

1. In a device of the character described, a clamp for holding a saw blade in fixed position, a generally rectangular frame having telescoping end members whereby the spacing of the side members can be adjusted, one side member of the frame being pivotally connected, for adjustment, to said clamp, a block slidably and pivotally mounted on the opposite side member of the frame for bodily movement longitudinally of and pivotal movement about said last mentioned frame member, a guide member pivoted, for angular adjustment, to said block for movement therewith, a carriage slidably mounted in said guide way for movement toward and from the saw, spaced clamps on said carriage for securing the ends of a file to said carriage substantially in parallel relation to the path of movement of the carriage in the guide member and means to adjust the spacing of said clamps.

35 2. In a device of the character described, a clamp for holding a saw blade in fixed position, a generally rectangular frame, one side member of the frame being pivotally connected, for adjustment, to said clamp, a block slidably and pivotally mounted on the opposite frame member for bodily movement longitudinally of and pivotal movement about said last named frame

member, a guide member pivoted, for angular adjustment, to said block for movement therewith, a carriage slidably mounted in said guide for movement toward and from the saw, a clamp on the carriage for securing the rear end of a file, a rod adjustably mounted on said carriage and provided at its forward end with a clamp for securing the forward end of the file, said file clamps being so arranged with respect to the carriage that the file is positioned substantially in parallel relation to the path of movement of the carriage in the guide member, and a vertically adjustable bar removably mounted on the first named frame member and positioned between said rod and the file for engagement by the rod 15 to limit the downward movement of the file against the saw.

3. In a device of the character described, a clamp for holding a saw blade, a generally rectangular frame, one side member of which is pivoted, for adjustment, to said clamp in parallel relation to the saw, means for supporting and guiding a file comprising a block slidably and rotatably mounted on the opposite side member of the frame for bodily movement longitudinally 25 of and for rotation around said last named member, a pair of channel guides arranged in back to back relation on opposite sides of the block with their channels parallel, clamping means for securing the channel guides to the block in adjusted angular position with respect to the saw, a carriage slidably mounted in the uppermost of said channel guides for reciprocation toward and from the saw, and means for clamping a file to said carriage in parallel relation to the path of movement of the carriage in the guide member, said carriage being removable from its channel guide to permit reversal of the angle of the guides by a 180° rotation of the block, and the parts carried thereby, about 40 the supporting frame member.

CARL ANDERSON.
